UNITED STATES PATENT OFFICE.

ZEBULON HUNT AND EDWIN HUNT, OF HUDSON, NEW YORK.

STOVE ATTACHMENT.

SPECIFICATION forming part of Letters Patent No. 284,017, dated August 28, 1883.

Application filed May 26, 1883. (No model.)

To all whom it may concern:

Be it known that we, ZEBULON HUNT and EDWIN HUNT, both citizens of the United States of America, residing at Hudson, in the 5 county of Columbia and State of New York, have invented certain new and useful Improvements in Stove Attachments, of which the following is a specification, reference being had therein to the accompanying drawings.

10 This invention relates to an improvement in that class of stove attachments designed to be placed over the stove-pipe collar to utilize the large portion of heat that passes up the chimney; and the invention consists in the peculiar 15 construction, arrangement, and combination of parts, hereinafter more fully described and claimed.

Figure 1 in the accompanying drawings represents a plan view of the attachment; Fig. 2, 20 a front view thereof; Fig. 3, a section through the line xx in Fig. 1.

A represents the base of the attachment, provided with flaring walls a , rising therefrom on all sides, preferably cast in one piece with 25 the base, and having a hole, b , which fits over the pipe-collar on the stove. In one side is a hole, through which is passed one end of the rod C of the damper D . The base is provided with standards e , forming bearings for the 30 damper-rod and a support for the top plate, E . This plate has preferably three holes, e , which should be provided with suitable covers, and also a collar, f , adapted to receive the stove-pipe. On the back and both ends is 35 shown an upwardly and outwardly flaring margin or flange, g , to keep articles from falling off or being shoved off accidentally. The front edge of the top plate is turned downward to facilitate the sliding of pots, saucepans, &c., off of the attachment onto the stove 40 below, and there is a rib at h , which serves the double purpose of strengthening the top and as a stop for the damper when in its raised position.

45 At i are shown two projections on the front side of the base, through which bolts are passed, which bolts also pass through suitable holes made in the top plate of the stove, whereby not only are the two parts of the attachment 50 secured together, but the attachment is fast-

ened to the stove and held in the desired position without the necessity of any other support.

The location of one of the holes immediately over the pipe-collar in the stove will be found to be particularly useful, as the heated products of combustion as they pass upward through said collar will strike directly upon any pot or vessel set over or in said hole. 55

The damper will also be found a very effective adjunct to the attachment, as by its use 60 there can either be a direct draft to the collar and stove-pipe, or the products of combustion can be divided, so as to take a circuitous course, and thus heat any pot or other vessel placed over or in the end holes. A permanent 65 partition may be used in place of the damper D , if preferred.

It will be observed that the front side of the attachment is curved inward between the projections i and the receptacle for the pipe-collar on the stove, which admits of large pots or 70 kettles being placed over the back holes in the stove without coming in contact with the front side of the attachment, as they would do if said front side were straight. The walls of the 75 base-plate being made flaring admits of said plate and walls being made in one piece, whereby not only is the first cost of fitting less, but the base is made so strong thereby, the walls forming strengthening-ribs, that no support 80 other than the bolts that fasten the attachment to the stove is needed.

What we claim as new is—

1. In a stove attachment designed to be secured to the top back portion of a stove, a 85 base-plate, A ; provided with flaring walls a , and an opening for a pipe-collar, in combination with the top plate, E , provided with suitable boiler-holes and a pipe-collar, substantially as described. 90

2. The combination, with the stove attachment A E , designed to be secured to the top back portion of a stove, of the rod C and damper D , constructed to lie flat on the base-plate and to be raised to a vertical position, substantially as described. 95

3. In a stove attachment designed to be secured to the top back portion of a stove, the combination, with the base-plate A , provided with flaring walls and an opening for a pipe- 100

collar, of the top plate, E, having a raised flange, and provided with suitable boiler-holes and a pipe-collar, substantially as described.

4. An attachment for stoves, provided with an opening for the pipe-collar of the stove, a collar for the stove-pipe, and an opening for a boiler immediately over the opening for the pipe-collar of the stove, substantially as described.
5. In a stove attachment designed to be secured to the top back portion of a stove, an aperture for the reception of the pipe-collar of the stove, a collar for the reception of the

stove-pipe, and a division-plate between the two, constructed to compel the heated products of combustion to pass around each end of said division, substantially as and for the purpose specified.

In testimony whereof we affix our signatures in presence of two witnesses.

ZEBULON HUNT.
EDWIN HUNT.
